Primary Examiner — John Windmuller*Assistant Examiner* — Luqman McNeil(74) *Attorney, Agent, or Firm* — Richard L. Miller(57) **CLAIM**

The ornamental design for a sun shield with solar powered light, as shown and described.

DESCRIPTION

FIG. 1 is a top plan view of a sun shield with solar powered light showing my new design;

FIG. 2 is a front elevational view thereof;

FIG. 3 is a bottom plan view thereof;

FIG. 4 is a rear elevational view thereof; and,

FIG. 5 is a left side elevational view thereof, it being understood that the right side view is a mirror image thereof.

1 Claim, 3 Drawing Sheets(56)
